G. B. NICHOLS

SWIMMING DEVICE

Filed March 8, 1926

George B. Nichols

By F. E. Sharrow

Attorney

UNITED STATES PATENT OFFICE.

GEORGE B. NICHOLS, OF AKRON, OHIO.

SWIMMING DEVICE.

Application filed March 8, 1926. Serial No. 93,011.

This invention relates to swimming devices and has particular reference to new and novel improvements in inflatable floats adapted for use in sustaining the wearer in the water.

Objects of the invention are to provide a float, of simple, durable construction, which may be manufactured at a low cost and which when worn will sustain a bather 10 in the water in a proper swimming position.

A further object is to provide a float which will be of light weight and which when not in use may be folded to occupy a minimum of space whereby it may be formed 15 in a compact bundle which may be conveniently carried.

Another object is to provide a float of the class above indicated which may be quickly and conveniently secured to the 20 body of a bather and used without restraining the free movement of the arms and legs.

A particular object of is to provide a float which will present a relatively sharp, straight edge to the path of travel and which 25 when worn by a swimmer will offer a minimum amount of resistance to the water and will not materially retard the swimmer's progress.

The above objects are accomplished and 30 additional ends are attained by the novel construction, combination and arrangement of parts hereinafter described and illustrated in the accompanying drawing in which I have shown a preferred form of the 35 invention, it being understood that the invention is capable of various adaptations and that changes and modifications may be made or resort had to substitutions which come within the spirit of the invention as 40 set forth in the appended claims.

In the drawings like numerals of reference are used to denote like parts as the same may appear in any of the several views and in which:—

45 Figure 1 is a rear elevational view of a float construction in accordance with this invention, showing the same in an inflated condition.

Figure 2 is a central, longitudinally sectional view taken as indicated by the lines 50 2—2 of Figure 1.

Figure 3 is a cross sectional view taken as indicated by the lines 3—3 of Figure 1.

55 Figure 4 is a cross sectional view showing a tube as it is formed preparatory to

manufacturing a float constructed in accordance with this invention.

Proceeding now to a detailed description of the invention with reference to the particular adaptation thereof disclosed in the drawing, the numeral 6 is used to denote the main body of the float which is in the form of a tube preferably composed of elastic rubber, but which may be formed of any suitable material. The tube 6 is normally 60 cylindrical and the wall thereof is thickened along one side thereof. The thickened portion 7 extends around approximately one half of the tube. The tube is closed at each end by flattening the tube along each edge 65 of the thickened portion 7 and cementing, vulcanizing or otherwise securing the opposite sides of the wall together to form a flat end portion 8 on the upper end of the tube and a like flat end portion 9 on the lower 70 end thereof.

It will thus be seen that each end portion 8 and 9 is in the form of a flat substantially rectangular portion of rubber which is substantially thicker than either the forward 80 or rear portion of the tube 6. While the tube is preferably composed of elastic rubber, the double thickness of the end portions 8 and 9 forms relatively stiff fins at each end of the body 6. The said fins are 85 positioned in the same plane which extends longitudinally through said tube. As the front wall of the tube is substantially thicker than the rear wall thereof, the rear wall will be more elastic and will bulge outwardly 90 while the forward wall will remain relatively flat. The body will be enlarged at a point midway between the end portions 8 and 9, the wall converging to said flat end portions. The opposite sides of the wall of the cavity 95 5 meet in a straight line as at 14 at each end of the tube.

The numeral 10 denotes a belt which is composed of a strip of elastic rubber. The end portions of the strip 10 are positioned in abutting relation flat against the rear face of the lower flattened portion 8 and is cemented or vulcanized thereto. The strip 10 thus forms an endless belt adapted to be positioned around the waist of the wearer. 100 As shown in the drawings the belt 10 is vulcanized to the flattened portion 8, but it may otherwise be suitably secured thereto. The numerals 11 and 12 denote straps, one end of each strap is secured to the forward 105 110

face of the flattened portion 9, at the corner thereof so as to project upwardly therefrom. Each strap 11 and 12 has its opposite ends secured flat against the opposite corner portion as shown in the drawing and is cemented or vulcanized thereto, but it is understood that said straps may be otherwise suitably secured thereto.

The numeral 15 denotes an inflation stem which may be of ordinary or improved construction and which is secured in the wall of the tube 6 so as to project rearwardly therefrom at a point intermediate its length. The inflation stem 15 is provided with a suitable valve whereby the tube may be inflated and retained in an inflated condition.

In use, the tube 6 is placed in a vertical position on the back of the wearer and the arms are positioned through the loops 11 and 12. The belt 12 is positioned about the waist of the wearer thereby securing the float in a vertical position on the back of the wearer.

It will be seen that in this position, the relatively stiff sharp fin 9 is presented to the path of travel and the tapering forward and rearward position of the wall of the tube 6 forms a streamline body which will offer a minimum amount of resistance to the water whereby the progress of a wearer when swimming through the water will not be impeded.

Having thus illustrated my invention and described the same in detail, what I claim as new and desire to secure by Letters Patent is:—

1. An inflatable float comprising a normally cylindrical elastic body, a relatively

stiff elastic fin projecting from each end thereof, said fins formed by flattening the tube at each end thereof and securing the opposite walls together, a belt strap secured to one of said fins and arm straps secured to the other fin.

2. In a swimmer's float, a flexible hollow body provided over approximately half its extent with a longitudinally extending thickened portion, the body being folded flat at each end thereof and the opposite sides of the wall joined to form outwardly projecting diametrically arranged flat flexible fins.

3. In a swimmer's float, an elastic tube provided over approximately half its extent with a longitudinally extending thickened portion, the tube being folded flat at each end thereof and the opposite sides of the wall joined to form outwardly projecting diametrically arranged flat flexible fins and means secured to said fins to fasten the float to the body.

4. In a swimmer's float, a flexible hollow body provided over approximately half its extent with a longitudinally extending thickened portion, the body being folded flat at each end thereof and the opposite sides of the wall joined thereby forming an outwardly projecting diametrically arranged flat flexible fin projecting from each end of the body, endless elastic straps secured to each corner of the upper fin and an endless elastic belt secured to the lower fin.

In testimony whereof I have hereunto set my hand.

GEORGE B. NICHOLS.
